Patented Feb. 22, 1916.

UNITED STATES PATENT OFFICE.

RICCARDO GIRARDELLI, OF ROME, ITALY.

APPARATUS FOR ADJUSTING THE DIRECTIONS OF GUNS.

1,172,979.

Specification of Letters Patent. Patented Feb. 22, 1916.

Application filed January 9, 1914. Serial No. 811,252.

To all whom it may concern:

Be it known that I, RICCARDO GIRARDELLI, a citizen of the Kingdom of Italy, residing at Rome, Italy, have invented certain new and useful Improvements in Apparatus for Adjusting the Directions of Guns, of which the following is a specification.

The subject matter of this invention is an apparatus for adjusting the directions of guns, which, by adjusting the direction and elevation of one of these guns, enables a second gun to be simultaneously and automatically directed upon the target.

The invention will be described with reference to the accompanying drawings, in which—

Figure 1 is a plan view, partially in section, of the apparatus forming the subject matter of this invention. Fig. 2 is a vertical section on the line 2—2 of Fig. 1 looking in the direction of the arrow x , with certain parts in a different position, and Fig. 3 is a triangle showing the relative position of the two guns and the target.

In Fig. 3 the point 1 denotes the station of one of the guns, the point 2 the station of the other gun, and the point 3 the position of the target. The two guns are supposed to be pivot guns. To adjust the direction of the gun mounted at the point 1 (which will be hereafter denoted the primary gun) an electromotor A is employed, and to adjust the direction of the gun mounted at the point 2 an electromotor B is employed. It is also assumed that the direction of the primary gun is effected from a distant observing station through the medium of an electrical controlling apparatus operated from a distance, and that the transmitter (not shown), located at the observing station, is provided for example with the apparatus described in the pending application dated Sept. 24, 1910, Serial No. 583,642. This transmitter is connected by a three phase conductor C with the motor A which serves to adjust the direction of the primary gun.

The directing mechanism of the primary gun consists substantially of a worm wheel D mounted coaxially with the axis of the pivot, and worm e^1 mounted on the shaft E of the motor A and gearing into said

worm wheel D. The shaft E also carries a second worm e^2 . This latter gears with a worm wheel F, which is rigidly mounted on a column F¹ carried in a frame G and formed with a longitudinal slot f², and the conditions are so arranged that the column F¹ and the worm wheel D must rotate in the same direction and through equal angles. The point through which the axis of rotation of the column is projected in Fig. 1 is denoted by 1'.

Underneath the column F¹ there is pivotally mounted, by means of a pin g¹ an arm H formed with a longitudinal slot h¹, the axis of the pin g¹ is parallel with the axis of rotation of the column F¹ and is projected through the point 3' in Fig. 1. An arm f³, extending in a radial direction, is so mounted on the lower end of the column F¹, that the angle which its direction forms with the fixed direction 1', 3', is always equal to the angle which the plane of elevation of the gun, projected along the straight line s, s¹ in Fig. 1, forms with the fixed direction 1, 2. If the frame G be so arranged, as is assumed in the drawing for the sake of clearness, that the fixed direction 1', 3' is parallel to the fixed direction 1, 2, the direction of the arm f³ must consequently be always parallel with the straight line s, s¹. Upon the arm f³ is mounted a movable sleeve J, which is provided on its underside with a pin i¹, which enters a corresponding boring in a sliding piece K guided in the slot h¹ in the arm H. The point through which the axis of the pin i¹ is projected in Fig. 1 is denoted by 2'.

The sleeve bears, under the pressure of a helical spring M which tends to thrust it inward, with a roller i² against a cam N, which is mounted between the side boundary walls of the slot f² and pivotally mounted on the column F¹ by means of a pin f⁴. Above the cam N there is pivotally mounted on the column F¹, by means of a pin f⁵, a flat bar P, which is suitably connected to the barrel of the primary gun, for example by means of an electrical controlling apparatus, not shown, operated from a distance, so that it always possesses the same elevation as the gun barrel. The flat bar P is connected by a connecting rod Q to an arm n¹ on the cam

N, which is so arranged and of such dimensions that a pivoted parallelogram is formed and the cam N therefore compelled to always rotate through the same angle as the flat bar P or the gun barrel.

As will be seen from the above description, the length of the distance 1', 2' is obviously dependent upon the elevation of the barrel of the primary gun or else on the distance of the target corresponding to this elevation. The law, according to which the length of the distance 1', 2' varies with the distance of the target is determined by the shape of the cam N. This shape is so chosen that the length of the distance 1', 2' is inversely proportional, within the fire limits concerned of the primary gun, to the distance of the target for which the primary gun is adjusted, and moreover is based upon a proportionality factor which is equal to the product of the (invariable) proportional numbers of the distances 1', 3' and 1, 2.

The arm H is provided with a toothed sector h^2 , engaging with a spur pinion n^1 , which is mounted on the switch shaft R of a transmitter g^2 mounted on the frame G. This transmitter is constructed in a similar manner to the transmitter located at the observing station, and communicates through a three phase conductor T with the motor B, which acts as a receiver and which serves to drive the directing mechanism of the gun mounted at 2. The motor B is a double motor and has two independent rotors, one of which can be rotated through the same angle as the shaft E of the motor A by means of the transmitter situated at the observing station through the medium of the conductor C and a conductor C^1 branching off therefrom. The angle of rotation of this rotor is therefore proportionally equal to the lateral angle of rotation of the primary gun.

The second rotor can be rotated by the transmitter g^2 , through the medium of the conductor T, through an angle which is proportionally equal to the angle of the switch shaft R of the transmitter, or the angle of rotation of the arm H. The angle of rotation of the switch shaft R and consequently also the angle of rotation of the second rotor is proportionally equal to the angle 1'-3'-2' indicated by character γ , between the center line of the arm H and the center line connecting the centers of pin g^1 and column F^1 and shaft R; it being assumed, as shown in Fig. 2, that the shaft R has its zero-position of rotation, when the two center lines referred to, are situated in the same vertical plane. The two rotors are suitably connected, by means of a differential gearing for example, to the shaft U of the motor B (which is adapted, by means of a worm u^1 mounted thereon and a worm wheel V gear-
ing therewith and coaxial with the axis of

the pivot of the gun mounted at the point, to impart to this gun the direction indicated by the straight line w , w^1). The movement of the rotors of motor B is transmitted in known manner to the shaft U in such a manner, that the angle of rotation of the shaft U, is equal to the algebraic sum of two angles, one of which is proportionally equal to the angle of rotation of the first, and the other to the angle of rotation of the second rotor.

The angle of rotation of the shaft U and the angle of rotation of the gun mounted at the point 2 proportionally equal thereto, is therefore equal to the algebraic sum of two angles, one of which is proportionally equal to the lateral angle of rotation of the primary gun, and the other to the angle 1'-3'-2'. It is therefore directly possible, so to arrange the conditions, as assumed here, that the lateral angle of rotation of the gun mounted at the point 2, measured from the direction 1, 2 in a clockwise sense, is equal to the algebraic sum of the lateral angle of rotation of the primary gun, (measured from the same direction and in the same sense) and the angle 1'-3'-2'. If the angle of rotation of the primary gun be denoted by α , the angle of rotation of the gun mounted at the point 2 by β , and the angle 1'-3'-2' by γ , the following relationship consequently exists:

$$\beta = \alpha + \gamma.$$

The apparatus herein described is used in the following manner. The transmitter situated at the observing station is first adjusted to correspond to the direction to be imparted to the primary gun. The adjustment imparted to this transmitter is transmitted through the medium of the conductor C to the motor A, and from this latter through the medium of the shaft E and the worm gearing e^1 D to the primary gun in such a manner that this latter is directed upon the target. The straight line s , s^1 then coincides with the straight line 1, 3, see Fig. 3, and

$$\alpha = \angle 2-1-3.$$

At the same time the column F^1 is rotated by the worm gearing e^2 F. Since during this rotation the direction of the arm f^3 is permanently parallel with the direction s , s^1 , the angle 3'-1'-2' is therefore

$$\alpha = \angle 3'-1'-2' = \angle 2-1-3.$$

After this the elevation corresponding to the distance 1, 3 of the target is imparted to the barrel of the primary gun, which operation may be accomplished also by electrical means for example from a separate transmitter situated at the observing station. Simultaneously with the gun barrel, the flat bar P also has the same elevation imparted to it, the sleeve J being adjusted by means of

the connecting rod Q, and the cam N, according to the above statements, to the distance

$$1'-2' = \frac{1-2 \times 1'-3'}{1-3}.$$

5 It follows therefore that

$$\frac{1'-2'}{1'-3'} = \frac{1-2}{1-3}$$

10 The triangles $1'-2'-3'$ and $1-2-3$ are consequently similar, since they agree in one angle and the ratio of the adjacent sides. Consequently in particular

$$15 \quad \gamma = (\angle 1'-3'-2') = \angle 1-3-2.$$

20 The rotation which the arm H has undergone during the rotation of the column F and the adjustment of the sleeve J, simultaneously caused the switch shaft R of the transmitter g^2 and the rotor of the motor, B, which is connected thereto by the conductor T, to be moved. The other rotor of the motor B has already received its adjustment through the medium of the conductors C and 25 C¹, during the adjustment of the transmitter which is mounted at the observing station and serves to adjust the direction of the primary gun. In consequence of the adjustments imparted to the two rotors, the 30 gun mounted at the point 2 has imparted to it, as above described, a direction which is determined by the angle

$$\beta = \alpha + \gamma.$$

35 Since now after making the adjustments above mentioned

$$\alpha = \angle 2-1-3$$

$$\gamma = \angle 1-3-2$$

40 as proved above, then

$$45 \quad \beta = \angle 2-1-3 + \angle 1-3-2.$$

The direction w, w^1 of the gun mounted at the point 2 must therefore coincide with the line 2, 3 (see Fig. 3), since the angular distance of the line 2, 3 measured from the direction 1, 2 in a clockwise sense, that is to say the external angle of the triangle 1, 2, 3 situated at the point 2 is likewise equal to

$$50 \quad \angle 2-1-3 + \angle 1-3-2.$$

The gun mounted at the point 2 has therefore been directed upon the target.

55 If in addition to the gun mounted at the point 2 other additional guns are to be directed laterally upon the target, this may be naturally accomplished by providing for each of such guns a separate apparatus of the same kind as that for the gun mounted at the point 2.

60 I claim:

1. In an apparatus for directing a secondary gun upon the same target simultaneously with and in consequence of the laying of a

primary gun; a training device (C A E e¹ D) and an elevating device for the primary gun; a training mechanism (U u¹ V) for said secondary gun, a distant controlling device (g² T B) for operating said mechanism, said controlling device having a transmitter (g²) connected both to said primary training device and said primary elevating device.

2. In an apparatus for directing a secondary gun upon the same target simultaneously with and in consequence of the laying of a primary gun; a training device and an elevating device for the primary gun; a training mechanism for said secondary gun; a distant controlling device comprising a receiver, a transmitter and a conductor between the two, said transmitter having driving connection both with said primary training device and said primary elevating device; a second conductor for said receiver connecting it with said primary training device for imparting angular adjustment to the secondary training mechanism independent of said transmitter but proportionally equal to the angle of training given to the primary gun.

3. In an apparatus for directing a secondary gun upon the same target simultaneously with and in consequence of the laying of a primary gun; a training device and an elevating device for the primary gun; a training mechanism for said secondary gun, a distant controlling device comprising a receiver, a transmitter and a conductor between the two; said transmitter having connection with a mechanical triangle, one side of which being fixed as to length and direction, another side having connection with said primary training device so as to always form an angle with said fixed side, of the same magnitude as the training angle of the primary gun; said other side also having connection with said primary elevating device whereby the length of said other side is adjustable according to the distance between the target and the primary gun; said transmitter connection thereby imparting angular adjustment to the transmitter proportionally equal to one of the other angles of the mechanical triangle; a second conductor for said receiver connecting it with said primary training device for imparting angular adjustment to the secondary training mechanism independent of said transmitter but proportionally equal to the angle of training given to the primary gun.

45 In testimony whereof I have affixed my signature in presence of two witnesses.
